SCREW-DOWN INDICATING APPARATUS

Robert H. Ellis and Howard N. Fry, Pittsburgh,
Pa., assignors to United Engineering & Foundry
Company, Pittsburgh, Pa., a corporation of
Pennsylvania

Application October 4, 1933, Serial No. 692,213

10 Claims. (Cl. 116—124)

This invention relates to rolling mills and more particularly to a system and apparatus for indicating to the operator of a rolling mill the setting of the working rolls which determine the dimensions of the roll pass.

It has been the customary practice in the past to provide rolling mills and especially mills of the variable pass type to which this invention has its broadest application with large clock-faced roll setting indicators which are mounted on the tops of the roll housings with their pointers connected to the roll-adjusting screws of the mill and their dials calibrated to indicate the roll adjustments. While such indicators may be satisfactory on blooming mills, slabbing mills or the like where the stock being rolled is several inches thick, they are not satisfactory for indicating the setting of the rolls on the modern strip mill where the thickness of the stock being rolled must be measured in thousandths of an inch. When operating the latter it is desirable for the operator of the mill to be able to keep his eyes on the material being rolled when he is operating the mill and particularly when he is adjusting the mill pass. This he can not do when these old type indicators are used, as he has to raise his eyes from the stock to the top of the mill in order to see the indicator.

Another objectionable feature of such indicators is that they can not be located at a point remote from the mill where it is frequently desirable to position the mill controls or to have such information available for other purposes. Furthermore, they are difficult and awkward to adjust when the mill is first started or when new rolls are placed in the mill, at which time it is necessary to give them an original setting.

In accordance with modern practice, rolling mills are usually controlled by electrical means in the form of various control devices which are usually mounted in a control panel located at a point removed from the mill and so positioned that the operator can supervise the operation of the mill without removing his eyes from the mill pass which is highly desirable. In keeping with this practice it is highly desirable to have indicators for indicating the roll settings of the mill to the operator which may be mounted in the control panel of the mill along with the various control devices used for controlling the mill and which may be readily and easily adjusted by the operator without any material alterations to effect its original or starting setting.

With the foregoing in mind it is an object of this invention to provide a system of apparatus

for indicating the setting of the rolls in a rolling mill which includes an indicating unit adapted to be positioned in any desired place either adjacent to or remote from the mill such as in the control panel for the mill, and which is simple and sturdy of construction as well as accurate in operation and easy and convenient to adjust to provide any original setting required.

Another object is to provide an indicator of this character on which the readings of the roll settings at both ends of the mill may be accurately read at a single glance and which, because of various conditions such as a difference in temperature of the roll necks, a difference in stretch of the roll housings, and a non-uniform shape of the material entering the mill, may be different, and the simultaneous reading of which may be highly desirable.

These and various other objects, as well as the various other novel features and advantages of the invention will be apparent when the following detailed description is read in conjunction with the accompanying drawings, of which Fig. 1 is a schematic diagram illustrating one embodiment of the invention; Fig. 1a, an end view of the mill schematically shown in plan in Fig. 1; Fig. 2 a plan view of an indicating unit such as shown in Fig. 1; Fig. 3 a composite sectional view taken on the lines III—III and III'—III'—III"—III"—III"—III"—III' of Fig. 2, the first-mentioned portion of the section extending through the left-hand adjusting element and the lower section of the indicator housing, and the latter through the portion of the indicator mounted on top of the lower housing section; Fig. 4 a section taken on the line IV—IV of Fig. 2; and Fig. 5 a plan view of a modification of the invention.

Referring in detail to the drawings and first to the embodiment of the invention illustrated in Figs. 1 to 4, inclusive, the numerals 1 and 2, Fig. 1, designate the roll-adjusting screws of a rolling mill and the numerals 3 and 4 a pair of screw-down motors arranged in a conventional manner for actuating these screws. As illustrated such motors are connected to a pair of aligned shafts 5 and 6 which are releasably connected together by a suitable clutch 7 which permits the screws 1 and 2 to be operated either jointly or individually. On these motor shafts 5 and 6 there is keyed a pair of worms 9 and 11 arranged to mesh with a pair of cooperating worm wheels 12 and 13 keyed to a pair of connecting shafts 14 and 15. These latter shafts are in turn equipped with a pair of worms 16 and 17 which

are arranged to mesh with a pair of worm wheels 18 and 19 splinedly mounted on the mill screws 1 and 2.

For producing electrical reaction corresponding to the vertical movement of the mill rolls when the screws 1 and 2 are turned by the screw-down motors 3 and 4 a pair of electrical devices in the nature of synchronous generators 21 and 22 and known to the trade as "selsyns" is connected. This connection is effected by a pair of pinions 23 and 24 mounted on the drive shafts of such devices and a pair of gears 25 and 26 connected to the screw shafts 14 and 15 with which the pinions are meshed.

These generators which are also referred to frequently as transmitters are electrically connected by suitable conductors 27 and 28 to a pair of cooperating synchronous motors or receivers 29 and 31 which may be located at any desired point such as beneath the control panel for the mill and are connected to operate suitable roll-setting indicators which will be presently described. The gearing connections for the transmitters 21 and 22 are so designed as to provide them with a movement relative to the screws 1 and 2 which may be conveniently and readily indicated by the indicating elements. Synchronous generators and motors or transmitters and receivers of this character which are capable of accurately communicating the mechanical movement of one to the other are so well known in the art that a detailed description and illustration of them is deemed unnecessary.

In the present embodiment of the invention the indicating elements referred to above are both incorporated, as clearly illustrated in Figs. 2, 3 and 4, in a single unit which is adapted to be conveniently mounted in a control panel and to so display such elements as to render them easily readable at a single glance.

Referring to these figures, this unit comprises a housing formed by a lower rectangular box-shaped section 32 and an upper round dish-shaped structure 33, which is the larger of the two and secured to the former by suitable bolts 34. In the center of the housings formed by these two sections there is arranged a pair of telescoping shafts 35 and 36. The inner of these is mounted at its lower end in a suitable bearing 37 located in the base of the lower housing section 32 and its upper end projects above the bottom of the upper housing section 33. The outer one is mounted in a suitable bearing 38 supported in the base of the upper housing section 33 with its lower end disposed above the base of the lower housing section 32 and its upper end projected above the bottom of the upper housing section but below the upper end of the inner shaft 35.

On the lower ends of such shafts 35 and 36 there is keyed a pair of worm wheels 39 and 41 which are meshed on the opposite sides of the telescoping shafts with a pair of worms 42 and 43, respectively, mounted on a pair of horizontally disposed shafts 44 and 45. These latter shafts are mounted in suitable bearings in the sides of the lower housing section 32 with their ends projecting beyond the outer walls of such housing. To one end of the lower shaft 44 the synchronous motor 31 is connected by a suitable coupling 47 while the opposite end of the upper shaft 45 is similarly connected by a suitable coupling 48 to the synchronous motor 29.

Consequently, through this arrangement the two shafts 35 and 36 are actuated in direct pro-

portion to the movement of the mill screws when the screw-down motors are operated. To provide for indicating such movement a pair of pointers 49 and 51 is mounted on the upper ends of shafts 35 and 36 to rotate over the face of a calibrated dial 52 mounted in the upper housing section 33 in spaced relation with the lower wall thereof, being spaced from such wall by a spacer member 53 and secured thereto by a series of bolts 54. Over the top of this dial there is mounted a transparent covering 55 which is held in place by a ring-shaped frame 56 mounted on a flange 57 provided about the top of the dish-shaped housing section 33. Such flange is also employed for securing the indicator in the control panel 58.

In order that the pointers 49 and 51 may be readily adjusted to place them in their proper position when the mill is set in operation the shafts 44 and 45 to which the synchronous motors 20 are connected are projected beyond the opposite sides of the roll housing section 32 to which the motors 29 and 31, respectively, are connected and equipped with a pair of miter gears 59 and 61. For engaging these a pair of miter gears 66 and 67 is mounted on a pair of vertically aligned shafts 62 and 63 secured in suitable brackets 64 and 65 attached to the housing section 33, their upper ends being projected through suitable openings above the top of the unit and equipped with turning wheels 50 and 60. To normally hold these latter gears out of engagement with the miter gears 59 and 61 coil springs 68 and 69 are mounted under compression on the shafts 62 and 63 with their lower ends bearing against a pair of collars 71 and 72 held in the brackets 64 and 65 and their upper ends bearing against a pair of collars 73 and 74 keyed to the shafts 62 and 63. With such an arrangement when it is desired to adjust the pointers 49 and 51 the wheels 50 and 60 and the shafts 62 and 63 are merely forced downwardly against the pressure of the springs 68 and 69 until the miter gears 66 and 67 engage the miter gears 59 and 61 and the wheels 50 and 60 then turn until the desired setting is obtained.

As will be readily appreciated the dial 52 may be calibrated in any suitable fashion determined by the relative movement imparted to the pointers by the mill screws. For example, when used with a cold strip mill, drives for the pointers are preferably provided which permit the dial to be calibrated in thousandths of an inch and so that one complete turn of each counter represents a displacement of the roll settings equal to one-tenth of an inch.

To provide for indicating to the operator the number of revolutions which the pointers are revolved when the rolls are adjusted for a pass exceeding one-tenth of an inch a pair of suitable counters 75 and 76 of well-known construction may be mounted on the 0-50 diameter of the dial and provided with tripping triggers 77 and 78 disposed to be engaged respectively by the pointers 49 and 51 as such pointers are rotated. To prevent the lower pointer 51 from striking the trigger 77 of the upper counter, it may be made sufficiently shorter than the upper pointer 49 so that it will miss the upper counter trigger 77 as it is rotated. Counters of this character capable of operating in either direction are so well known in the art that a detailed description of them is deemed unnecessary, and obviously they may be designed to operate in either direction and to record the readings which they make in terms 75

of inches and/or fractions thereof as may be desired.

In the operation of the invention the mill is first adjusted to produce the thickness of material desired, and the pointers 49 and 51 on the indicator are then adjusted by the screws 50 and 60 to accurately designate the dimension of the pass. Thereafter, if the operator desires to change the mill pass he may do so, and obtain an accurate setting, by watching the movement of the pointers 49 and 51 as he controls the operation of the screw-down motors. Through the use of the two concentrically mounted pointers he can with ease either operate the screw-down motors individually by disengaging the clutch 7 connecting such motors together or operate both of them simultaneously.

If for any reason it becomes necessary to adjust just one end of the mill rolls somewhat differently than the other in order to produce a uniform piece of material, as it frequently does especially in case the opposite ends of the rolls are heated to different temperatures, or the stretch of the roll housings is slightly different, or the material entering the mill is not uniform, such difference in adjustment will be set up by the pointers, and as such discrepancies will very probably be the same for all sizes of passes, the operator after once having determined what it is, can readily maintain it for all settings. Thus the problem of adjusting the rolls is materially simplified, as the two pointers which are concentrically mounted may be always maintained in the same relative position when adjusted.

35 In the modification of the invention illustrated in Fig. 5, in place of a rotatable pointer and dial type of indicator a pair of counters 81 and 82 is used, the operating shafts 83 and 84 thereof being connected through suitable clutches 85 and 40 86 to the drive shafts of the synchronous motors 29 and 31, such clutches being preferably adapted to permit the counters to be adjusted by hand when desired to correct them for original settings. In operation this latter embodiment of the 45 invention is similar to that previously described, and for convenience in observation the counters are mounted one above the other so that they may be also read at a single glance by the operator.

50 According to the provisions of the patent statutes, we have explained the principle and mode of operation of our invention and have illustrated and described what we now consider to represent its best embodiment. However, we desire to have 55 it understood that, within the scope of the appended claims, the invention may be practiced otherwise than as specifically illustrated and described.

We claim:

60 1. In combination with a rolling mill, means for adjusting the two ends of a roll thereof to thereby selectively vary the size of the roll pass, a synchronous generator connected to said roll adjusting means at each end of the mill, means 65 included in each of said connections for multiplying the movement imparted to said generator as compared to that imparted to said roll, a pair of synchronous motors located remotely with respect to said roll adjusting means and electrically connected to said generators, and means 70 operatively connected to each of said motors for indicating respectively the roll adjustment at each end of the mill, said latter means being located in juxtaposition.

75 2. In combination with a rolling mill, means

for individually adjusting the spacing between the two ends of the mill rolls to vary the size of the roll pass, a synchronous generator coupled to each of said roll-adjusting means, a pair of synchronous motors remotely located with respect to said roll-adjusting means and electrically connected to said generators, a pair of independently operable shafts mounted one within the other and separately connected to said motors, a pointer mounted on each of said shafts, and a dial 10 arranged behind said pointers calibrated in terms of the roll settings whereby the settings of the rolls at both ends of the mill are separately indicated by the positions of said pointers.

3. In combination with a rolling mill, means 15 at the opposite ends of the mill for adjusting the spacing between the mill rolls to vary the size of the roll pass, a synchronous generator connected for rotation by each of said roll-adjusting means, a pair of synchronous motors located remotely with respect to the roll-adjusting means, and electrically connected to said generators, means calibrated in terms of the roll settings operably connected to each of said motors for indicating the roll settings and mounted adjacent 25 each other for simultaneous reading, and means for adjusting said indicators independently of the roll-adjusting means.

4. In combination with a rolling mill, means for individually adjusting the ends of one of the 30 mill rolls to vary the size of the roll pass, a synchronous generator coupled to each of said adjusting means for operation thereby, a pair of synchronous motors remotely located with respect to said roll-adjusting means and electrical- 35 ly connected to said generators, a pair of indicators adjustable with respect to each other and coupled to said motors in conjoint relation and adapted when operated thereby to indicate the settings of the mill rolls, and means op- 40 erative without respect to the roll-adjusting means for varying the settings of said indicators.

5. In combination with a rolling mill, a roll- 45 setting indicator comprising a housing, a pair of telescopically arranged shafts mounted in said housing, a pair of pointers mounted at one end of said shafts, a common dial calibrated in terms of the roll settings of the mill mounted adjacent said pointers, a pair of gear wheels mounted on said shafts, a pair of pinions meshed with said 50 wheels mounted on drive shafts extended through said housing, a pair of synchronous motors coupled to said latter shafts, means for adjusting the two ends of the rolls of the mill to vary the roll pass, a pair of synchronous generators cou- 55 plied to said roll-adjusting means for operation thereby, and means electrically connecting said motors to be synchronously operated by said generators.

6. In combination with a rolling mill, a roll- 60 setting indicator comprising a housing, a pair of telescopically arranged shafts mounted in said housing, a pair of pointers mounted at one end of said shafts, a common dial calibrated in terms of the roll settings of the mill mounted adj- 65 acent said pointers, a pair of gear wheels mounted on said shafts, a pair of pinions meshed with said wheels mounted on drive shafts extended through said housing, a pair of synchronous motors coupled to said latter shafts, means for ad- 70 justing the two ends of the rolls of the mill to vary the roll pass, a pair of synchronous genera- 75 tors coupled to said roll-adjusting means for operation thereby, means electrically connecting said motors to be synchronously operated by said 75

generators, and means resiliently supported on said housing for releasably engaging said shafts and adjusting said pointers.

7. In combination with a rolling mill, a roll-setting indicator comprising a housing, a pair of telescopically arranged shafts mounted in said housing, a pair of pointers mounted at one end of said shafts, a common dial calibrated in terms of the roll settings of the mill mounted adjacent 10 said pointers, a counter unit mounted in said dial with means provided thereon disposed to be actuated by one of said pointers as the latter is rotated therepast, a pair of gear wheels mounted on said shafts, a pair of pinions meshed 15 with said wheels mounted on drive shafts extended through said housing, a pair of synchronous motors coupled to said latter shafts, means for adjusting the two ends of the rolls of the mill to vary the roll pass, a pair of synchronous 20 generators coupled to said roll-adjusting means for operation thereby, and means electrically connecting said motors to be synchronously operated by said generators.

8. A roll-setting indicator for use in indicating 25 the setting of the rolls in a rolling mill comprising, a housing, a pair of shafts mounted one within the other in said housing, the lower end of one shaft being supported in a wall provided in the base of said housing, the upper end of the 30 other being supported in a wall provided in the upper portion of the housing, a pair of pointers mounted on the upper ends of said shafts, a calibrated dial disposed below said pointers, a pair

of worm wheels mounted on the lower ends of said shafts, a pair of worms meshed with said wheels mounted on a second pair of shafts disposed at right angles to the first-mentioned shafts with their ends supported in but projected 5 through the sides of said housing, a driving connection at one end of each of said last-mentioned shafts, and means for releasably engaging the other ends of said shafts to adjust said pointers mounted on the sides of said housing. 10

9. In combination with a rolling mill, means for adjusting the ends of one of the working rolls to vary the size of the roll pass, a pair of electroresponsive indicating elements located at a common point remote from said roll-adjusting 15 means for indicating the roll setting at the two ends of the mill, and electro-operative means coupled to said roll-adjusting means and electrically connected to said indicating means for operating the latter.

10. In combination with a rolling mill, means at the opposite ends of the mill for adjusting the spacing between the mill rolls to vary the size of the roll pass, an electro-synchronous transmitter operatively connected to each of said roll 25 adjusting means, a remotely located electro-syn-
chronous receiver electrically connected to each
of said transmitters and a counter type indi-
cator for indicating the roll adjustments con-
nected to each of said receivers, said indicators 30 being arranged in readable juxtaposition.
